UNITED STATES PATENT OFFICE.

JOSEPH STUART, OF PITTSBURGH, PENNSYLVANIA.

WATCHMAN'S REGISTERING APPARATUS.

1,405,727.

Specification of Letters Patent. Patented Feb. 7, 1922.

Application filed February 25, 1919. Serial No. 279,191.

To all whom it may concern:

Be it known that I, JOSEPH STUART, a citizen of the United States, residing at Pittsburgh, in the county of Allegheny and State 5 of Pennsylvania, have invented certain new and useful Improvements in Watchmen's Registering Apparatus, of which the following is a specification.

The prime object of my invention is to 10 provide a simple and efficient watchman's registering apparatus, and more particularly an apparatus of the character referred to designed for use in buildings to which the watchman does not have access but which 15 he is required to visit during certain periods.

In the accompanying drawings which illustrate an application of my invention, Fig. 1 is a part vertical sectional view and a part elevational view of an apparatus embodying my invention applied to the door 20 of a building;

Fig. 2 is a vertical sectional view taken on line 2—2 of Fig. 1; and

Fig. 3 is a horizontal sectional view taken 25 on line 3—3 of Fig. 1.

Referring to the drawings, 1 designates a casing designed to be secured to the interior of a door 2 of a building or at some other convenient point inside of a building. As 30 shown, casing 1 is provided with a door 3 through which access may be had to its interior, and 4 designates an elongated casing projecting downwardly from and in communication with the interior of casing 1, the 35 guideway being disposed at right angles to the plane of the supporting structure 2, that is, perpendicular to the supporting structure. Casing 4 is designed to receive and guide a tape or strip 5 of paper or other 40 suitable material, as it is wound off a reel or revoluble tape or strip carrier 6. As shown, tape 5 is provided with graduated markings 7.

In the embodiment of my invention as 45 shown, the tape is designed to be discharged from or wound off its carrier intermittently. That is to say, a certain amount of tape is wound from the carrier during a predetermined period of time, for example, eight or 50 ten hours during the night, after which period, the movement of the tape or strip is arrested for a predetermined number of hours, after which its carrier is again actuated to discharge the tape.

55 The means employed for moving the tape from its reel or carrier includes a clockwork

8 of any suitable construction. The clock-work is disposed within the casing 1 and is supported on the back plate 9 thereof by means of brackets 10. 11 designates the winding key of the clockwork. As this clock mechanism per se forms no part of the present invention, I consider it unnecessary to fully describe the same.

In addition to the clockwork and adapted 65 to cooperate therewith, I employ a wheel 12, said wheel being mounted on an end of a rotatable shaft 13 of the clock mechanism and adapted to be revolved thereby. Wheel 12 is of relatively large diameter and has 70 a portion only of its periphery provided with teeth. As illustrated, the toothed portion 14 of the wheel extends for about one-half of the circumference, the remaining portion of the periphery of the wheel being 75 smooth.

Tape carrier or reel 6 is loosely mounted on a fixed rod 15 projecting from the back wall of casing 1, and carries a pinion 16. Interposed between pinion 16 and wheel 12 80 is an idler pinion 17, the teeth of the latter being adapted to mesh with the toothed portion 14 of wheel 12 and the teeth of pinion 16.

For the purpose of marking the tape to 85 designate the fact that the watchman has visited the building, a suitable tool or key 18 is provided. This key is carried by the watchman and is designed to be inserted through a key-hole in the door or other 90 part of the building to which the registering apparatus is applied. As shown, the key is formed with a stem having a right angled projection 19 adapted to be entered into the guide casing 4 through an opening *a* 95 thereof. Casing 4 is also formed with an opening *b* (see Fig. 3) directly opposite opening *a*. These openings permit the key to be manipulated in such a manner as to mark the tape as the latter is fed down 100 through the guide-casing 4. In the form shown, the portion 19 of the key is designed to penetrate the tape, but it is evident that some other form of tool may be employed for marking the tape.

By having the markings 7 of the tape 105 designate hours and fractions thereof, it will be understood that approximately the exact time or times the watchman has registered may be ascertained.

In the use of the invention, that portion of the tape bearing the marks made by the

watchman or a portion of the end of the tape that should contain the marks or registrations, during a predetermined period of time, is severed from the continuous strip 5 after the expiration of said period.

What I claim is:

1. A registering apparatus comprising a casing adapted to be secured to a supporting structure, a tape guide depending from said 10 casing, said tape guide being constructed to hold the tape perpendicular to the plane of the supporting structure when the casing is secured thereto and provided with an opening therein for a marker, a removable marker 15 adapted to be moved through an arc and arranged to be projected through the opening when so moved, and means in the casing for moving the tape through the depending guide.
- 20 2. A registering apparatus comprising a casing adapted to be secured to a supporting structure, a tape guide depending from said casing, said tape guide being constructed to hold the tape at right angles to the plane of a supporting structure to which the casing may be secured and provided with registering openings, a removable marker comprising a shaft having a radially extending arm arranged to be swung through an 25 arc and to project through the registering openings when so moved, and means in the casing for intermittently causing a strip of 30 tape to gravitate through the guide.
3. In combination, a supporting structure 35 having an opening therein, a casing secured thereto, tape feeding mechanism in the cas-

ing, a guide perpendicular to the supporting structure and extending downwardly from the casing, said guide having an opening 40 therein adjacent the opening in the supporting structure, and a removable key adapted to project through the opening in the supporting structure and having an angular extension thereon adapted to be projected through the opening in said guide and travel 45 through an arcuate path upon turning the key whereby a marking will be made in a piece of tape in the guide.

4. The combination with a supporting structure, of a casing secured to one side thereof, a guide-way having registering openings therein carried by the casing and in a plane perpendicular to the plane of the supporting structure, means in the casing for advancing a strip of tape through the 55 guide, and removable means operable from the opposite side of said supporting structure for marking on said tape, said means comprising a key having a stem portion passing transversely through the door and having a marking portion extending at right angles to the stem and arranged to travel in an arc when the stem is rotated, said marking portion being adapted to be projected through said registering openings in the 60 guide-way when the key is rotated.

In testimony whereof I affix my signature in presence of two witnesses.

JOSEPH STUART.
